UNITED STATES PATENT OFFICE.

FRANK O. WELLS, OF THE UNITED STATES NAVY, ASSIGNOR OF ONE-HALF TO WALTER H. LASSING, OF THE UNITED STATES NAVY.

INCINERATOR.

1,232,138.

Specification of Letters Patent.

Patented July 3, 1917.

Application filed November 27, 1916. Serial No. 133,709.

To all whom it may concern:

Be it known that I, FRANK O. WELLS, a citizen of the United States, stationed on board the U. S. S. *New York*, have invented 5 certain new and useful Improvements in Incinerators; and I do hereby declare the following to be a full, clear, and exact description of the invention, such as will enable others skilled in the art to which it 10 appertains to make and use the same.

The present invention relates to improvements in incinerators, and has for an object to provide an incinerator for use more particularly on board ship where a strong and 15 well anchored structure is required to withstand the rolling motion of the ship and the vibration due to gun firing.

Broadly stated, the improved incinerator is built up of fire brick or other suitable material; such structure being inclosed in a 20 metallic casing and anchored together by transverse baffle walls.

It is a further object of the present invention to provide an improved incinerator 25 having a perforated hearth upon which refuse is deposited through a charging door, which may be located in the front or rear end walls, or in the side walls or top of the structure; such perforated hearth being 30 also preferably arched and disposed above a fire box, from which the products of combustion ascend through the perforations in the hearth and are also directed into contact with the refuse from above by baffle 35 walls.

With these and other objects in view the invention consists in the novel details of construction and combinations of parts more fully hereinafter disclosed and particularly 40 pointed out in the claims.

In the accompanying drawings forming a part of this application, and in which similar reference symbols indicate corresponding parts in the several views:

45 Figure 1 is a front elevational view of an incinerator constructed in accordance with the present invention.

Fig. 2 is a longitudinal sectional view taken on the line 2—2 in Fig. 1, with the oil burner removed.

50 Fig. 3 is a transverse sectional view taken on the line 3—3 in Fig. 2.

Fig. 4 is a horizontal sectional view taken on the line 4—4 in Fig. 3.

Fig. 5 is a fragmentary sectional view 55 of a slightly modified form of the invention, illustrating the charging door as in the rear of the incinerator structure.

Fig. 6 is a similar view illustrating a further modification in which the charging 60 door is located in the side of the incinerating structure.

Fig. 7 is a fragmentary transverse sectional view taken on the line 7—7 in Fig. 6; and

65 Fig. 8 is a fragmentary sectional view illustrating the charging door as in the top of the incinerator structure.

Referring more particularly to the drawings, the incinerator structure is built up 70 preferably, though not necessarily so, in the rectangular general formation shown, of fire brick, or other suitable material; the structure being arranged to provide outer side walls 1 and 2, connected by a front 75 wall 3 and a rear wall 4.

Spaced from the outer side walls 1 and 2 are longitudinal interior walls 5 and 6, providing passages 23 and 24 therebetween for receiving the products of combustion and 80 directing the same to the chimney, as will hereinafter more clearly appear.

Between the interior longitudinal walls 5 and 6 is suspended a hearth or floor 7, which is advantageously formed, as see 85 more particularly Fig. 4, by assembling bricks in rows to break-joint and with their ends spaced apart to provide openings 8 through which the products of combustion may arise from the fire box beneath, as indicated by the arrows in Fig. 2.

Immediately beneath the arched hearth 7 and between the interior longitudinal walls 5 and 6 is the fire box 9, wherein is a grate 10, constituted, as advantageously appearing in Figs. 2 and 3, of spaced fire bricks or other units assembled on angle bars 11. Beneath the grate 10 is the usual ash pit 12, there being a discharge pipe 13 at the rear thereof for carrying off any liquid matter 100 that may have found its way thereinto. The fire bricks 9 and ash pit 12 are accessible, respectively, through doors 14 and 15 of any suitable character, and shown to be mounted in the front wall 3 of the incinerator structure and a metallic framework or front plate 16 secured thereover.

The hearth 7 preferably extends from the

front wall 3 of the structure to within a short distance of the rear wall 4, providing a vertical flue 17 therebetween through which the major portion of the products of combustion from the fire box 9 will find its way into the incinerating chamber above such hearth 7, the path of the products through this vertical flue 17 being clearly indicated by the arrows in Fig. 2.

At the rear of the arched hearth 7 is advantageously erected a bridge wall 18, also of fire brick, or other suitable construction, and preferably stepped or inclined, as shown in Fig. 2, to coöperate with the inclined rear wall 19 of a baffle 20 supported in the longitudinal interior walls 5 and 6, slightly in advance of the bridge wall 18, and preferably reinforced by channel beams, or other means, 21. The combined effect of the bridge wall 18 and baffle 20 is to direct the products of combustion issuing up through the flue 17 down against and into the refuse or other matter which has been deposited upon the perforated hearth 7, thereby acting conjointly with the products of combustion entering through the openings 8 in the hearth 7 to burn thoroughly and completely all of the combustible matter.

The material to be consumed is introduced into the incinerating chamber and deposited on the hearth 7 through a charging door 22, shown in Figs. 1 and 2 to be located in the front wall 3 of the incinerator structure and to have its mountings in the frame or front plate 16; although this charging door 22 may be located in the rear wall 4, or in either of the side walls or top of the structure, as will hereinafter be more fully referred to in the particular description of Figs. 5 to 8 inclusive.

There are openings 25 and 26, respectively, in the interior longitudinal walls 5 and 6, preferably in their upper forward corners, where the products of combustion will arise, and which are provided to receive such products of combustion and direct the same into the lateral passages 23 and 24. At their rear ends these passages are widened, as indicated at 27 and 28, communicating at these points with the branches of a chimney 29. Intermediately, the lateral passages 23 and 24 are supplied with deflectors 30 and 31, which extend from the top of the incinerator structure down substantially to points midway of the height thereof, and have the function of encountering the products of combustion on their way to the chimney 29 and directing the same downwardly and into contact with the exterior surfaces of the interior walls 5 and 6 for communicating the heat thereof to all parts of the same, and thereby having the effect of maintaining the interior at a high temperature, such as is advantageous in drying out the garbage, refuse, or other mate-

rial, and which prevents a rapid dissipation of the heat from the incinerating chamber and fire box.

At their forward ends the lateral passages 23 and 24 are shown in Fig. 1 to be accessible for cleaning through doors or plugs 32 and 33, also mounted in the framework or front plate 16.

The incinerator structure as a whole, built up as above described, is for purposes of strength, and where the same is to be erected on shipboard, to be inclosed in a metallic casing preferably consisting of angle posts 34 disposed at the corners of the fire brick structure, and to which are secured, as by rivets, bolts, or other means 35, metallic plates or sheets 36 incasing and binding together the whole structure, as will appear from an inspection of Figs. 2, 3 and 4. Between the plates or metallic sheets 36 and the respective walls of the incinerator structure is advantageously interposed one or more layers of asbestos 37 for conserving and preventing rapid dissipation of the heat, and also for refractory purposes.

Referring now more particularly to Fig. 5, it will be here seen that the charging door 38 is located in the rear wall 4 of the incinerator structure, the other parts of the construction being similar to those described with reference to Figs. 1 to 4 inclusive, as indicated by the same reference characters, with the exception of the baffle which is disposed horizontally, as shown at 39, providing a ledge upon which the refuse is received and from which it is pushed by a suitable implement upon the hearth 7. The baffle 39 is formed with an inner head 40 extending downwardly from the horizontally extending portion 39 and being formed with the inclined wall 41 for coöperating with the bridge wall 18 to direct the products of combustion down upon and into contact with the material on the hearth 7. The other parts (not shown) may be similar to those already described and shown in the first form of the invention, and this construction may be applied to other forms of incinerators as desired.

Referring now to Figs. 6 and 7, a charging door is here shown at 42 to be located in one side wall 2 of the incinerator structure. The door 42, in this instance, opens into a passage 43 which extends through the adjacent interior wall 6, the deflector 31 being thereby dispensed with, as the wall of the passage 43 serves the same purpose. The remaining parts are similar to those above described, and are similarly numbered.

In Fig. 8 the charging door is designated as 44, and is shown to be placed on the roof of the incinerator structure, there being no alteration of the other parts necessary for this position of the door.

The present invention, in the embodiment

shown in Figs. 1 to 4, inclusive, has been built up on the U. S. S. *New York*. After severe trials such structure has been found to withstand the rolling motion of the ship and the vibration, shocks, and jars incident to gun firing, which have quite generally prohibited the installation of incinerators on ships, former structures readily falling in. On shipboard it will probably be advantageous to provide the charging door either in the front or rear, or one of the side walls in the absence of head space; but I do not desire to restrict myself to the use of this incinerator on shipboard alone, as it will be apparent that the same may be installed on land with excellent results. The incinerator may be fired by wood or other combustible material introduced through the door 14, and placed upon the grate 10. The use of an oil or gas burner may be preferable, however, and such a burner is indicated in Fig. 1 at 50, there being supply pipes 51 and 52, one for the oil or gas and the other for steam, air or water.

It is obvious that those skilled in the art may vary the details of construction and arrangements of parts without departing from the spirit of my invention, and therefore I do not wish to be limited to such features except as may be required by the claims.

I claim:

1. In an incinerator, a refractory structure including front and rear walls, inner and outer spaced side walls, a fire box contained between said inner walls, an arched hearth above said fire box and supported between said inner walls, a bridge wall on said hearth and extending between said inner walls, a baffle above said hearth and bridge wall and also extending between said inner walls, passages between said inner and outer walls in communication with the hearth chamber, and baffle plates in said passages and extending between said inner and outer walls, substantially as described.

2. In an incinerator, the combination of a structure, an incinerating chamber in said structure, a perforated hearth for receiving the material to be consumed, a fire box directly beneath said hearth and having uninterrupted access to the material through

said perforations in said hearth, a flue placing said fire box in communication with said chamber, a bridge wall on said hearth, a baffle in said chamber coöperating with the bridge wall to direct the products of combustion from said flue into contact with the material on said hearth, lateral passages in communication with said incinerating chamber and extending longitudinally thereof, and deflectors in said passages, substantially as described.

3. In an incinerator, the combination of a structure providing an incinerating chamber, a perforated hearth for said chamber, a door in said structure for introducing material to said hearth, a fire box located directly beneath said hearth and having uninterrupted communication with said chamber through the perforations therein, a flue placing said fire box in communication with the incinerating chamber, a baffle having an inclined face for receiving the products of combustion from said flue and directing same against the material on said hearth, a metallic casing for said structure, and a heat retaining and refractory lining interposed between said casing and structure, substantially as described.

4. In an incinerator, the combination of a brick structure, an incinerating chamber immediately beneath the top of said structure, a perforated arched hearth in said chamber, a door for introducing the material to be consumed to said hearth, a fire box immediately beneath said hearth, a flue placing said fire box in communication with said incinerating chamber, a baffle having an inclined face for encountering the products of combustion received from said flue and directing the same downwardly against the material on said hearth, lateral passages in communication with said incinerating chamber and extending horizontally and longitudinally thereof, deflectors in the upper portion of said passages for directing the products downwardly thereabout, a chimney in communication with said passages, a metallic casing for said structure, and a heat retaining material interposed between said casing and structure.

In testimony whereof, I affix my signature.

FRANK O. WELLS.
